(57) **CLAIM**

The ornamental design for an ink cartridge for printer, as shown and described.

DESCRIPTION

FIG. 1 is a top, front and left side perspective view of an ink cartridge for printer showing our new design;

FIG. 2 is a front view thereof;

FIG. 3 is a rear view thereof;

FIG. 4 is a top plan view thereof;

FIG. 5 is a bottom view thereof;

FIG. 6 is a right side view thereof;

FIG. 7 is a left side view thereof;

FIG. 8 is a top, front and left side perspective view of a second embodiment of an ink cartridge for printer;

FIG. 9 is a front view thereof;

FIG. 10 is a rear view thereof;

FIG. 11 is a top plan view thereof;

FIG. 12 is a bottom view thereof;

FIG. 13 is a right side view thereof;

FIG. 14 is a left side view thereof;

FIG. 15 is a top, front and left side perspective view of a third embodiment of an ink cartridge for printer;

FIG. 16 is a front view thereof;

FIG. 17 is a rear view thereof;

FIG. 18 is a top plan view thereof;

FIG. 19 is a bottom view thereof;

FIG. 20 is a right side view thereof; and,

FIG. 21 is a left side view thereof.
